S. H. MOON ET AL

PROJECTION SCREEN

Filed June 4, 1921

Inventors-
Samuel Henry Moon and
Harry Hamilton Moon.
By: P. Anger Atty.

UNITED STATES PATENT OFFICE.

SAMUEL HENRY MOON AND HARRY HAMILTON MOON, OF BIRMINGHAM, ENGLAND.

PROJECTION SCREEN.

Application filed June 4, 1921. Serial No. 474,983.

To all whom it may concern:

Be it known that we, SAMUEL HENRY MOON and HARRY HAMILTON MOON, both subjects of the Kingdom of Great Britain, 5 both residing at 10 and 12 Holloway Head, Birmingham, in the county of Warwick, England, mechanical engineers, have invented certain new and useful Improvements in or Relating to Projection Screens, 10 of which the following is a specification.

This invention relates to screens for cinematograph and like projecting apparatus, of the type in which the screen has a surface which is curved in the cross-section of 15 the screen.

Screens of this character assume considerable dimensions and are usually of a character such that as a whole they are not fitted for transport or installation in existing buildings. In an existing building it is not convenient to manufacture a screen of this character within the building for installation, and it is one of the objects of the present invention to provide for the ready 25 transport and installation of a screen of this character.

With this object in view, the present invention comprehends a screen of this character which is manufactured in sections adapted to be aggregated or assembled to produce the complete screen. These sections can thus be manufactured in any suitable vicinity, transported by road or rail, conveyed into a building through the ordinary doorways and readily installed in position within the building expeditiously and without creating inconvenience.

Advantageously the screen according to the present invention is of concave form involving a surface which is curved in the vertical and also in the horizontal transverse sections of the screen.

The invention, however, extends to a screen having only a simple curve as distinguished from this spherical or substantially spherical formation.

In order that this invention may be clearly understood and readily carried into practice, reference may be had to the appended explanatory drawing, which illus-

trates in perspective a cinematograph screen for receiving the picture to be exhibited to an audience, constructed according to the present invention.

In a convenient embodiment of the present invention, we construct a screen *a* with a concave surface *b* adapted to exhibit the picture projected from a cinematograph apparatus. Such a screen may, for instance, be composed of a wooden back-ground *c* or 55 reinforcing provision carrying at its front surface a layer of plaster which is formed to present the desired concave surface. Advantageously the screen is in sections for convenience in installation and transport, 60 and each section may be of box-like formation at the rear so that the box sections can be secured together in any appropriate manner. In the embodiment shown, the screen is divided at *d* into four sections, but 65 obviously a larger number of divisions may be incorporated where necessary or desirable. Alternatively, the screen may be constructed of sheet metal or any other appropriate material.

While, in the embodiment shown, the screen surface is of concave formation and curved both laterally and vertically, the curve may occur in only a vertical, lateral, or inclined direction. In any of these formations the surface may be convex or bulged instead of concave or hollowed.

What we claim as our invention and desire to secure by Letters Patent is:—

A screen for a cinematograph and like projecting apparatus, in which the screen has a surface which is curved in the cross-section of the screen, wherein the said screen is manufactured in sections adapted to be aggregated or assembled to produce the complete screen, each section being of box-like formation at the rear, and presenting a plane rear face, adapting the same to bear against a flat wall of a building wherein the screen is to be installed.

In witness whereof we have hereunto set our hands.

SAMUEL HENRY MOON.
HARRY HAMILTON MOON.
